UNITED STATES PATENT OFFICE

JOHN W. MAILLOT, OF NORTH ATTLEBOROUGH, MASSACHUSETTS, ASSIGNOR
TO FRANK M. WHITING & CO., OF SAME PLACE.

DESIGN FOR A SPOON.

SPECIFICATION forming part of Design No. 22,251, dated March 7, 1893.

Application filed January 28, 1893. Serial No. 460,165. Term of patent 3½ years.

To all whom it may concern:

Be it known that I, JOHN W. MAILLOT, a citizen of the United States, residing at North Attleborough, in the county of Bristol, State of Massachusetts, have invented and produced a new and original Design for Spoons, Forks, and the Like, of which the following is a specification.

In the drawings:—Figure 1, is a front view 10 of the spoon. Fig. 2, is a rear view of the handle.

The design while shown applied to a spoon may also as will be readily understood, be applied to forks or the like. The handle end 15 of the spoon shown at A, has a marginal scroll extending around it from the point 1, to the point a, with inwardly extending branches at the points 2, 3, and 4 and at the lower ends of the scroll. Along the narrow 20 part of the handle and below the marginal scroll is an elongated approximately S shaped scroll beginning at its lower end in a shell like ornament 6, extending diagonally upward with branches on each side and terminating in a nearly circular upper end 5. Be-

low the lower end 6 is a series of flutings 7, extending downwardly therefrom. The opposite side or back of the spoon is made as shown in Fig. 2, the upper part of the handle being provided also with a marginal scroll 30 and inwardly extending branches. At the base or lower ends of the marginal scroll, scrolls 8, 8, begin extending downwardly along the margin of the narrow part of the handle, to an ornamental shell 9, and from 35 this part 9, flutings extend downwardly as in the front face. The spoon bowl is also ornamented as in Fig. 1, by side scrolls 10, and flutings 11, extending into the bowl along the margin. 40

I claim—

The design for a spoon herein shown and described.

In testimony whereof I affix my signature in presence of two witnesses.

JOHN W. MAILLOT.
